2 SHEETS-SHEET 2.

UNITED STATES PATENT OFFICE.

OMAR N. GARDNER, OF JAMESTOWN, NEW YORK.

CRANE AND DERRICK.

1,077,467.

Specification of Letters Patent.

Patented Nov. 4, 1913.

Application filed February 7, 1913. Serial No. 746,827.

To all whom it may concern:

Be it known that I, OMAR N. GARDNER, a citizen of the United States, residing at Jamestown, in the county of Chautauqua and State of New York, have invented certain new and useful Improvements in Cranes and Derricks, of which the following is a specification.

This invention relates to certain new and useful improvements in that type of hoisting mechanism known as cranes and derricks, and the invention consists, essentially, in an improved means for raising and lowering a boom and hoisting the load with the same fall of cables, thereby giving to a one-drum hoisting engine substantially the same capacity as a two-drum engine and making a two-drum engine have substantially the same capacity as a three drum engine, etc., the invention comprehending improved means for controlling the raising and lowering of the load and also the raising and lowering of the boom about its pivotal center by the same means which raises and lowers the load.

The invention further consists of the parts, and the constructions, arrangements and combinations of parts which I will hereinafter describe and claim.

In the accompanying drawings forming part of this specification and in which similar reference characters indicate like parts in the several views; Figure 1 represents a side elevation of a crane or derrick embodying the salient features of my invention and showing the same in connection with a double drum hoisting engine. Fig. 2 is a rear view of the mast and boom showing in section one form of clutch adapted to lock the boom to the mast. Fig. 3 is an enlarged plan view of the upper end of the boom. Fig. 4 is a side elevation of the same. Fig. 5 is a sectional detail of the boom showing the weighted hoisting block in position for raising the boom and showing pairs of pulleys around which the hoisting cable passes.

This invention relates generally to the type of hoisting mechanism shown and described in my prior Patent No. 1,041,266, dated October 15, 1912, but in the present instance I dispense with the movable jib of said patent in favor of improved means for raising and lowering the boom and hoisting loads with a one-drum engine, thereby

saving the additional drum and the attention which it has required in prior devices of this type.

The invention also comprehends the raising and lowering of the boom and the hoisting of the load with the same fall of cables with the single whip doubled upon itself, or a double whip doubled upon itself, or a triple whip doubled upon itself, which may be done by adding additional sets of sheaves for the whips.

While the present invention is shown in connection with a revoluble mast, it will be understood that it is applicable to any of the well known forms of cranes or derricks whether of the rotary or so-called "stiff leg" type, or to any arrangement of hoisting mechanism employing a pivoted boom and a hoisting block and cable.

For purposes of illustration, and as disclosing one embodiment of my invention, I have shown the same in connection with a vertical mast, 10, the lower end of which is appropriately stepped or seated in a bearing, 11, of a framework, 12, which may be in the form of a traveling carriage upon which is mounted a suitable engine, 13, a pair of hoisting drums, 14, and 15, with their usual accessories, and the drums, 16, around which passes a cable, 17, which leads past idler pulleys, 18, to and around a horizontal bull-wheel, 19, appropriately fixed to the lower end of the mast and suitably braced and strengthened in any suitable manner, said mast having its upper portion connected to the frame of the carriage by suitable tension rods, 20, whereby the mast is appropriately secured to resist the severe work to which it is subjected. Connected with the mast I have also shown the braces or "stiff legs" 21. These parts may be of the usual or any approved construction and form no essential part of my present invention.

The boom, 22, may be of any well known form and construction; for instance it may be formed of metal with parallel sides spaced apart and adapted to contain between them the sheaves or pulleys around which the cables employed are adapted to pass, said boom having its lower end pivotally mounted at 23 in a base frame, 24, bolted to the mast, and about which pivot the boom is permitted to swing in a vertical direction.

Within the lower part of the mast is mounted a sprocket wheel idler, 24, and adjacent thereto is a sprocket wheel, 28, to which is connected one member, 26, of a suitable clutch, which member may be of any type and is adapted to co-act with a companion clutch member, 25, slidably splined on a fixed shaft, 27, and adapted to operate in a manner substantially as disclosed for the similar clutch of my aforesaid prior patent. The sprocket wheel, 28, is herein shown as being in rear of the mast but the position of this wheel is immaterial and, therefore, it may be otherwise located relatively to the mast, and around said sprocket wheel passes a cable or chain, 29, which is designed to lock the holding boom in its adjusted position when the aforesaid clutch is operated to cause its members, 25-26, to engage.

One end of the holding chain or cable is connected to a pulley block, 30, the cable thence passing downwardly along the upper surface of the boom to and under the idler sprocket wheel, 24, and to and around the sprocket wheel, 28, and it thence extends forwardly under a fair lead idler, 31, and upwardly under a fair-lead idler, 32, mounted on the boom and adapted to support the central portion of the boom when said boom is of considerable length; the holding chain or cable thence extends to and around a sheave or pulley, 33, mounted between the lower ends of a pair of swinging links, 34, pivotally mounted to the upper or head end of the boom, said holding chain or cable thence extending toward the mast and being fixedly secured thereto near the upper end. The pulley block, 30, contains a sheave or pulley, 35, around which passes an operating cable, 36, from which the load is suspended, as I will now describe. The operating cable, 36, is controlled by the winding drum, 14, to which the opposite ends of the cable are attached and from which drum the two parts of the cable extend over pulleys, 36', one on each side of the mast, and to and around pulleys, 37, 37', and thence to and around pulleys, 38, 38', in the pulley block, 30', from which the load is suspended, the parts of the cable passing from the pulleys, 38, 38' upwardly over pulleys, 39, 39', in the outer end of the boom and thence extending downwardly along the upper portion of the boom to and around the pulley, 35, which is thus mounted in the bight of the cable and is arranged at right angles to the pulleys, 37 and 39.

It will thus be seen that the cable is of a double character or what is known as a "double whip" and that it has twice the power of the usual "double whip" with the rapidity of what is termed a single double whip; it will, also, be understood that a single set of pulleys or more than the double

set herein shown may be used without departing from the spirit of my invention, and that the number of sets of sheaves used will depend upon the number of returned or doubled portions which are to be given the single operating cable, from which the load is suspended.

In the drawings I have illustrated the load as in the form of a dumping excavating bucket, but it will be understood that this is representative of any load or any kind of bucket, "clam-shell" or otherwise, well known in this art, and which I may use in connection with my hoisting devices.

From the foregoing it will be understood that when the winding drum, 14, is operated to wind the cable, 36, the latter will, through the connections described, cause the weight to be lifted and this operation continues until the pulley block, 30', carrying the pulleys, 38 and 38', engages the upper end of the boom. If now the clutch, 25-26, which connects the boom to the mast is released so as to unlock the holding chain or cable, 29, the continued winding of the drum, 14, will result in the boom swinging about its pivotal connection, 23, so that its outer end may be raised to a higher elevation, as indicated by the dotted lines in Fig. 1.

During this action the pulley block, 30, is caused to move upwardly along the boom and by being connected with the holding chain or cable, 29, it causes this cable to pay out toward the upper end of the boom and to correspondingly pull upon the fixed point of the cable where it connects with the mast, thus resulting in the boom being moved from its lower to its higher position.

To lower the boom the operator causes the drum, 14, to unwind the operating cable, 36, and as the boom lowers the cable at the same time pulls upon the holding cable or chain, 29, and thereby causes the pulley, 30, to move downwardly along the upper side of the boom in response to the lowering of said boom and until the boom has been moved to its desired position. When this position has been obtained the clutch, 25-26 is operated to lock the holding chain, thereby preserving the position of the boom, while the further unwinding of the operating cable, 36, results in the pulley block, 30', lowering relatively to the upper end of the boom to permit of its engagement with another load.

To assist the pulley block, 30', with its pulleys, 38 and 38', returning to a position where it may engage a load, I may weight this block by the addition of suitable cast iron or other disks, 40, as shown in Fig. 5, and which disks may serve to engage the upper end of the boom when the hoisting block is raised to the dotted position shown in Fig. 1. The disks, 40, are preferably of circular form and they not only serve as a weight to insure the "down-haul" of the

hoisting block, but being circular they provide a perfect bearing for the boom when on the upward haul of the hoisting block they contact with the lower portion of suitable hoods, 41, with which the outer end of the boom is provided, as shown in Figs. 1 and 4.

In Fig. 3, the boom is shown as composed of metal sections appropriately bolted together and rigidly spaced apart, but this construction is purely optional.

From the foregoing it will be understood that my invention has in view the raising and lowering of a boom and the hoisting of a load with the same fall of cables thereby making a one-drum hoisting engine have the same capacity and perform the same labor as the two-drum engine heretofore used, or to make a two-drum engine perform the work of the three-drum engine now used in this art. To operate a "clam-shell" rig and to raise the boom thereof usually requires a three-drum engine, but with my construction I have operated these same parts with a two-drum engine such as shown in the accompanying drawings and I accomplish the several results ascribed for my prior patented device before alluded to without requiring the use of a traveling jib. I may use what is known in this art as a single double whip, a double double whip, as shown, and a triple double whip by increasing or decreasing the number of sheaves with which the boom and the hoisting block are supplied. To this end I have shown in Fig. 1, at the top of the mast suitable fair lead sheaves or pulleys, 44-45, which may be utilized in two-drum work, the present description and drawing having particular reference to the one-drum engine for operating both the load and the boom.

Having thus described my invention what I claim as new and desire to secure by Letters Patent is:—

1. In a device of the character described, the combination with a mast, a boom mounted to swing on a horizontal axis, and a load attaching means, of a cable having its opposite ends adapted to connect with a winding drum; a shiftable pulley block through which an intermediate portion of the cable is rove, said cable being guided over the upper portion of the boom and through the load attaching means, a boom hoisting cable rove between the boom and the mast and having one end connected to the shiftable pulley block in opposition to said cable and the opposite end secured to said mast, pulleys around which the intermediate portion of said boom hoisting cable is guided, and means for locking the said boom hoisting cable against movement whereby the shiftable pulley block is held in a fixed position relatively to the boom.

2. In a device of the character described, the combination with a mast, a boom mount-

ed to swing on a horizontal axis, and a load attaching means, of a cable having its opposite ends adapted to connect with a winding drum, a shiftable pulley block through which an intermediate portion of the cable is rove, 70 said cable being guided over the upper portion of the boom and through the load attaching means, a boom hoisting cable rove between the boom and the mast and having one end connected to the shiftable pulley 75 block in opposition to said cable and the opposite end secured to said mast, pulleys around which the intermediate portion of said boom hoisting cable is guided, means for locking the said boom hoisting cable 80 against movement whereby the shiftable pulley block is held in a fixed position relatively to the boom, and means for releasing said boom hoisting cable from its locked position to permit the shiftable pulley block 85 to move in response to changes in the vertical height of the boom.

3. In a device of the character described, the combination with a vertical mast, a boom mounted to swing on a horizontal axis, and a hoisting block, of a cable having its opposite ends adapted to connect with a winding drum, a shiftable pulley block through which a looped intermediate portion of the cable is rove, said cable being guided over the upper portion of the boom and through the hoisting block, a boom hoisting cable rove between the boom and the mast and having one end connected to the shiftable pulley 95 block in opposition to said cable and the opposite end secured to said mast, pulleys at the base of the mast and on the outer portion of the boom around which the intermediate portion of said boom hoisting cable is guided, and means for releasably locking 100 said boom hoisting cable against movement whereby the shiftable pulley block is held in a fixed position relatively to the boom when the boom is in one position and is permitted to move relatively to the boom when said boom is moved to a different position.

4. In a device of the character described, having a boom mounted to swing on a horizontal axis, and a vertical mast, an operating cable having opposite end portions adapted to connect with a winding drum, a hoisting block through which the cable is rove, said cable returning from the hoisting block toward said mast, and provided with a loop in an intermediate portion, a pulley block carried in the loop of the cable, and shiftable therewith lengthwise of the boom in response to variations in the inclination of said boom, a boom operating cable connecting with the pulley block, 115 means associated with the boom operating cable for holding the same inactive while the load is being lifted toward the boom, and means for releasing the boom operating cable to enable the pulley block to shift its 120 position relatively to the boom.

5. In a device of the character described, the combination with a mast, a boom mount-

position on the boom in response to ascending and descending changes in the inclination of said boom.

5. In a device of the character described, 5 having a boom mounted to swing on a horizontal axis, and a vertical mast, an operating cable having the opposite end portions adapted to connect with a winding drum, a hoisting block through which the cable is 10 rove, said cable returning from the hoisting block toward said mast, and provided with a loop in an intermediate portion, a pulley block carried in the loop of the cable, and shiftable therewith lengthwise of the 15 boom in response to variations in the inclination of said boom, a boom operating cable connecting with the pulley block, means associated with the boom operating cable for holding the same inactive while the load is 20 being lifted toward the boom, and means for releasing the boom operating cable to enable the pulley block to shift its position on the boom in response to ascending and descending changes in the inclination of 25 said boom, said hoisting block adapted to engage the boom from below during the winding function of the first-named cable whereby the continued winding thereof causes the boom to be moved from a lower 30 to a higher elevation.
6. In a device of the character described, having a vertical mast, and a boom mounted to swing on a horizontal axis, an operating cable having the opposite end portions adapted 35 to connect with a winding drum, a hoisting block through which the cable is rove, said cable returning from the hoisting block toward said mast and provided with a loop in an intermediate portion, a pulley block 40 carried in the loop of the cable and shiftable lengthwise of the boom in response to variations in the inclination thereof, means connecting with the pulley block for releasably holding the same in a fixed position 45 while the load is being lifted toward the boom, said means comprising a boom

operating cable having one end connected to said pulley block and the opposite end connected to the mast, pulleys at the base of the mast and on the boom around which 50 an intermediate portion of said element passes, co-acting clutch members associated with one of said pulleys adapted to lock the same to prevent movement of the boom operating cable when the boom is in one 55 position, and to release said boom operating cable when the boom is to be moved vertically from one position to another.

7. In a device of the character described, the combination with a mast, of a boom 60 mounted to swing on a horizontal axis, a hoisting block, said block having a pair of pulleys and said boom having a pair of pulleys in its outer end, an operating cable having its ends adapted to connect with a 65 winding drum, and thence passing upwardly and over the pulleys in the boom and downwardly around the pulleys in the hoisting block, said cable having a portion extending along the boom and returned upon itself to 70 form a loop, a pulley block mounted in the loop of said cable, a flexible element having one end connected to said pulley block in opposition to said cable, pulleys at the base of the mast and boom around which said 75 element passes, a pivoted frame having a guide pulley near the upper portion of the boom around which the element passes, said element then being secured to the upper portion of the mast, and means for locking said element against movement whereby said pulley block is held in a fixed position relatively to the boom, said means adapted to release the flexible element to allow the pulley block to shift its position in response 80 to variations in the inclination of said boom.

In testimony whereof I affix my signature in presence of two witnesses.

OMAR N. GARDNER.
